Patented Aug. 24, 1920.

Fig. 2. Inventor Frank C. Nelson,

By William C. Linton.

Attorney

UNITED STATES PATENT OFFICE.

FRANK C. NELSON, OF CLARKSBURG, WEST VIRGINIA, ASSIGNOR OF ONE-HALF TO
GEORGE W. DE WITT, OF CLARKSBURG, WEST VIRGINIA.

CLOTHESLINE.

1,350,380.

Specification of Letters Patent. Patented Aug. 24, 1920.

Application filed March 20, 1920. Serial No. 367,325.

To all whom it may concern:

Be it known that I, FRANK C. NELSON, a citizen of the United States, and a resident of Clarksburg, county of Harrison, West Virginia, have invented certain new and useful Improvements in Clotheslines; and I do hereby declare that the following is a full, clear, and exact description of the invention, such as will enable others skilled in the art to which it appertains to make and use the same.

My invention has reference to improvement in supports and has for its principal object to provide a novel form of clothes line which by reason of its construction will be strong and durable and, also, will permit the arranging of clothes pins or similar securing devices thereon in such a manner as to permit the ready attaching of the same to clothes without any undue liability of disengagement therebetween, such as is often times caused by vibration of the line with the ultimate dropping of the pins from the line, thereby allowing the clothes to fall to the ground.

It is also an object of the invention to provide the line with a type of clothes pin which will positively engage articles to be secured thereby without doing damage to the same as by tearing or soiling them with rust or other disfiguring marks.

The foregoing, together with other advantageous, details and arrangements of parts of the improved device will be apparent from a reading of the following detailed description in connection with the accompanying drawings, in which:

Figure 1, is a fragmental perspective of the improved support.

Fig. 2, is a detail in side elevation of the type of clothes pin employed.

Fig. 3, is a similar view taken at right angles to the Fig. 2, and,

Fig. 4, is a side elevation of a slightly modified form of pin.

Having more specific reference to the drawings in connection with which like reference characters will designate corresponding parts throughout the several views, my improved clothes line or support may be stated to comprise spaced superposed parallel wires 1 and 2, the wire 2 being above the main or supporting wire 1 and of lighter gage; rings 3 are connected to their opposite ends, as shown in the Fig. 1 and

are engaged with the end of rigid or substantially rigid rods 4, which, in turn, are arranged in converging relation and engaged with connecting rings 5. These connecting rings 5, as will be noted, are positioned between the wires 1 and 2 by reason of the converging arrangement of the rods 4, and to secure the same to fixed supporting means, short pieces of wire 6 are engaged therewith at certain of their ends, and with posts 7 or similar supports at their remaining ends.

Bracing wires 8 may be, and preferably are connected to the rings 3 secured to the several ends of the wire 2 and to the upper ends of the posts 7 in order that said wire will be held taut and properly spaced from the wire 1.

To secure clothes or other articles to the improved line, I employ a particular form of clothes pin, consisting of several lengths of spring wire having an attaching loop 9 formed on its outer end which is provided with overlapping end portions whereby to permit the introduction of the wire 2 therebetween and the arrangement of the same in such loop, while a second and larger loop 10 is formed therein by twisting the wires at 11, the free portions of the wires then being crossed and bent longitudinally of the pin to permit the engaging of the same in inwardly tapering wooden jaws 12, between which the articles to be secured to the line are engaged.

If desired, the wires 1 and 2 of the line may be supplied with bracing members 13 consisting of lengths of substantially rigid wire having their opposite ends looped at 14 and connected to said wires at spaced intervals throughout their lengths.

In using my improved clothes line, the clothes or other articles to be supported thereon are arranged upon the line 1, whereupon, they are engaged by the pins which are slidable along the upper wire 2 to any desired point. Engagement of the pins with these articles is effected by squeezing the sides of the loop 10, thus causing the jaws 12 to be separated sufficiently to engage the articles therebetween. At this time the loops 10 are released.

Instead of the form of pin indicated in the first embodiment, I may employ a pin such as shown in the Fig. 4 wherein the wooden jaws 12 thereof are formed with

transversely alined openings 15 through which the main wire 1 is passed. Thus, it will be understood that in addition to providing a securing device between which portions of an article on said wire may be secured, the pins will also serve as braces between the several wires 1 and 2, dispensing with the use of separate braces 13. However, if desired, these braces 13 may be used 10 in conjunction with the modified pin, but obviously, their number may be decreased.

Of course any desired number of pins may be arranged upon the wire 2, such as conditions or preference may dictate. Further, 15 since these pins are secured to such wire, it will be appreciated that loss of the same by disengagement from the wire 1 will be prevented.

Manifestly, the construction shown is capable of considerable modification, and such modification as is within the scope of my claims, I consider within the spirit of my invention.

Having thus fully described my invention, 20 what I claim as new and desire to secure by Letters Patent is:—

1. A clothes pin comprising a resilient wire body having the strands of wire twisted to form an attaching loop at one end, a 25 larger loop formed at the lower end, the ex-

tremities of the strands of wire crossing one another at the lower end of said larger loop and terminating in parallel ends and an upwardly tapered wooden jaw engaged with each parallel end.

35

2. A clothes pin consisting of a body formed of two strands of wire twisted together adjacent their medial portions forming an upper attaching loop and a lower resilient loop, the lower free ends of said 40 wires being crossed and bent longitudinally of the body, a tapered jaw carried by each longitudinal end and said jaws having alining openings therein for the reception of a clothes supporting line substantially as and 45 for the purpose set forth.

3. The combination with a clothes line consisting of an upper and lower section, of a clothes pin detachably connected and supported by the upper section, a pair of spring 50 closed jaws formed with said pin and said jaws having alining openings therein for the reception of the lower section of the clothes line whereby clothes may be retained between said jaws and supported upon said 55 lower section substantially as and in the manner specified.

In witness whereof I have hereunto set my hand.

FRANK C. NELSON.
